UNITED STATES PATENT OFFICE.

WALTER SOPHER AND IRA A. HAMMOND, OF AINSWORTH, NEBRASKA.

AUTOMATIC VISE AND STOP FOR WORK-BENCHES.

1,308,922.

Specification of Letters Patent.

Patented July 8, 1919.

Application filed February 14, 1918, Serial No. 217,162. Renewed November 26, 1918. Serial No. 264,248.

To all whom it may concern:

Be it known that we, WALTER SOPHER and IRA A. HAMMOND, citizens of the United States, residing at Ainsworth, county of 5 Brown, and State of Nebraska, have invented certain new and useful Improvements in Automatic Vises and Stops for Work-Benches, of which the following is a specification.

10 This invention relates to an automatic vise and stop for work benches.

Our object is to provide a novel bench vise which will automatically grasp and securely hold a board when the latter is 15 pressed thereagainst and serve as a bench stop for the board, so that the latter will be arranged for any desired work, such as planing its edge, for instance. Our improved vise and stop embodies jaws which 20 coöperate with closing means, in turn actuatable by pushing the board thereagainst and so arranged that the greater the pressure, the more firmly is the board grasped. The operative parts are, preferably, mounted on a 25 platform which can be raised and lowered so that the vise and stop may be elevated for use, or, depressed so that the top of the work bench is level and free for any desired use.

30 The invention is not limited to use on a work bench for wood, nor is it limited to being constructed out of wooden parts, but it finds particular utility in connection with carpenter's work benches.

35 The invention is susceptible of modification in certain respects and we do not, therefore, limit ourselves to the details of construction disclosed.

In the accompanying drawings:

40 Figure 1, is a plan view of the invention applied to a work bench, parts of the bench and platform being broken away;

Fig. 2, a longitudinal section through the invention by itself;

45 Fig. 3, a cross-section thereof; and

Fig. 4, a detail view, partly in section, showing the vise in lowered position.

A section of an ordinary work bench is shown at 1 to illustrate the application of 50 the invention thereto. An opening 2 having been cut out of the bench top, the box-like frame 3 is suitably fitted thereto, with its top flush with the top of the bench.

Across the bottom of the frame 3 extend 55 pieces 4 having guides 5, and a bar 6 in

which is set a nut 7 having internal screw-threads; said nut being held by a plate 8.

The platform 9, which carries the operative parts of the vise and stop, is supported by a hand-screw 10 which extends through 60 the bar 6 and is engaged with the threads inside the nut 7; the upper end of the screw has a swiveled connection 11 with a plate 12 secured to the lower face of the platform. On turning the screw 10 the platform 9 may 65 be elevated for use, or, lowered so that its top will be flush with the top of the bench and form no obstruction when the bench is needed for other purposes.

The platform 9 is of box-like form and 70 contains the operative parts of the vise and stop; the top is preferably removable and it has a slot 13 for the entry of the board or other article which is to be held by the vise.

Slidable lengthwise within the platform 75 is a closing frame 14 comprising a cross-piece and jaws 15 having inclined, or wedge-faces 16, provided with dove-tail grooves 17. The faces 16 converge toward each other toward the entry end of the platform. The 80 cross-piece of the frame 14 carries a rod 18 which slides through a guide hole 19^a in a piece 19 fixed to the platform 9. A spring 20 normally presses the closing frame 14 toward the entry end of the platform. 85

Jaws 21 have inclined or wedge-shaped faces 22 coöoperating with the faces 16 and they are provided with dove-tail ribs 23 which fit within, and slide relatively to, the closing frame 14 when the latter is moved, 90 whereby the jaws are opened or closed. To prevent the jaws from sliding lengthwise of the platform, they are provided with pins 24 and 25 received in grooves 26 and 27 in the bottom and top of the platform. 95

When it is desired to use the vise and stop, it is elevated by turning the hand-screw 10, which feeds it upwardly through the fixed frame 3. The end of the board or article to be held by the vise and stop, is then inserted into the slot 13 and pressed against the end of the pusher rod 18. This action moves the closing frame 14 lengthwise of the platform, thereby causing the wedge-faces 16 by their coöperation with 105 the faces 22, to move the jaws 21 against the article, firmly gripping it. The rod 18 is of such length that the jaws may be brought almost together before the end of the article engages the piece 19. When the 110

article, or piece of lumber is withdrawn, the spring 20 restores the closing frame and the jaws to normal position. The harder the article or piece of lumber is pressed 5 against the rod 18, the firmer will the jaws 21 grip the article to be held.

Having thus described our invention what we claim as new and desire to secure by Letters Patent, is:

- 10 1. In an automatic vise and stop for work benches, the combination with slidable jaws, of a slidable closing device therefor, said jaws and closing device having engaging inclined faces, whereby the jaws may be closed
- 15 2. when the closing device is moved in one direction, and operating means for the closing device arranged so as to be engaged by the article which is to be held by the jaws.
- 20 3. In an automatic vise and stop for work benches, the combination with slidable jaws having inclined faces, and guiding means for said jaws, of a slidable closing device having inclined faces engaged with those on the jaws and provided with means slidably interlocking with the jaws so that the latter will move to or fro as the closing device is slid in one direction or the other, a spring for moving the closing device to cause the jaws to open; and a pin or rod

arranged to be engaged by the article to be held by the jaws when said article is entering the jaws, said pin or rod co-operating with the closing device for the purpose of closing the jaws by the pressure of the article to be held thereby.

35

3. A work bench provided with a platform having an open part, said platform being adapted to be raised or lowered and, when lowered, arranged flush with the top of the bench, raising and lowering means 40 for said platform, and a vise contained within the platform which is available for use through the open part of said platform.

4. A work bench provided with a platform which can be raised or lowered, raising and lowering means therefor, and a vise carried by said platform having operating means adapted to be engaged by an article which is to be held by said vise, whereby the vise may be closed on said article by 45 pressing the article into engagement with said operating means when the platform is in position for use.

45

In testimony whereof we hereunto affix our signatures.

WALTER SOPHER.
IRA A. HAMMOND.
